UNITED STATES PATENT OFFICE

2,460,250

ABRASIVE APPARATUS

Earle M. Chase, Springfield, Mass., assignor to
Porter-McLeod Machine Tool Co., Inc., Hat-
field, Mass., a corporation of Massachusetts

Application April 14, 1947, Serial No. 741,353

6 Claims. (Cl. 51—84)

1

This invention relates to improvements in abrasive apparatus.

The principal objects of the invention are directed to the provision of abrasive apparatus which is adapted for buffing, polishing, grinding and various abrading operations and while the novel features of the invention will be explained in connection with cutlery such as knives, table knives, and the like, it will be understood that the novel feature of the apparatus may be adapted for various purposes as may be desired.

According to special features of the invention, a pair of coacting abrasive rolls are provided in combination with means for moving a plurality of knife blades up and down and longitudinally between said rolls and also in combination with other means for moving said rolls towards and away from one another and the blades therebetween.

Said rolls are releasably supported at opposite ends and are rotated by means which is arranged to move adjacent and opposite ends of said rolls towards and away from one another. The supporting and rotating means at opposite ends of the rolls are operable independently of one another so that the axes of the rolls at one end thereof may be a relatively greater or lesser distance apart than at the other end. This is accomplished by novel means controlling the operation of the rolls in such a way that a predetermined pressure is applied to the rolls irrespective of the thickness of the blades between them.

With the foregoing and various other novel features and advantages and other objects of my invention as will become more apparent as the description proceeds, the invention consists in certain novel features of construction and in the combination and arrangement of parts as will be hereinafter more particularly pointed out in the claims hereunto annexed and more fully described and referred to in connection with the accompanying drawings wherein:

Figs. 1 and 2 are front and end elevational views showing abrasive apparatus embodying the novel features of the invention;

Fig. 3 is a sectional elevational view on the line 3—3 of Fig. 1;

Fig. 4 is a sectional plan view on the line 4—4 of Fig. 3;

Fig. 5 is a sectional elevational view on the line 5—5 of Fig. 1;

Fig. 6 is a sectional elevational view on the line 6—6 of Fig. 5;

Fig. 7 is a sectional plan view on the line 7—7 of Fig. 5;

Fig. 8 is a perspective view of one of the hangers for supporting the blade carrying device;

Fig. 9 is a plan view of the abrasive rolls of the apparatus;

2

Fig. 10 is a front elevational view at the front upper side of the apparatus showing the mechanism for operating the blade carrying device;

Fig. 11 is a sectional elevational view on the line 11—11 of Fig. 10;

Fig. 12 is a sectional plan view on the line 12—12 of Fig. 10;

Figs. 13 and 14 are front and end elevational views of the work or blade carrying device; and

Fig. 15 is a diagrammatic view to explain the operation of various cylinders of the apparatus.

Referring now to the drawings more in detail, the invention will be fully described.

The apparatus of the invention includes as shown in Figs. 1 and 2 a housing or casing 2 which encloses substantially all of the operating mechanism.

The housing 2 is provided with front and rear walls 4 and 6, end walls 8, inner end walls 9, vertical walls 10 disposed inwardly of the planes of the front and rear walls 4 and 6 and a horizontal wall 12. There is an opening 14 through the housing, as shown clearly in Fig. 1, across which extend a pair of coacting abrasive rolls 16 and mechanism 18 thereabove for supporting a knife carrier all of which will be described hereinafter.

It is intended that the housing be fabricated from sheet metal and constructed to enclose the operating mechanism so that as few components will be accessible as is necessary for the efficient operation of the apparatus.

The walls of the housing are provided with openings to provide access to the various operating compartments and components and these are closed by cover plates which may be removably secured thereto in any convenient manner. Such plates are indicated by 20 to 28 inc. Other walls and partitions are associated with the housing as will be apparent as the description proceeds.

The mechanism for supporting and rotating the abrasive rolls 16 will now be described with particular reference to Figs. 5, 6 and 7.

The mechanism to be described is disposed within the housing at its left hand end in Fig. 1. While supporting the ends of both rolls, only one of said rolls is driven thereby. There is a similar mechanism within the right-hand end of the housing for supporting the opposite ends of both rolls but the other roll is driven thereby. A description of the mechanism for one end of the rolls will be sufficient.

Inner and outer brackets 34 and 36 are fixed to wall 9 and to a horizontal partition 38 of the housing. Shafts 40 are oscillatable in the bearings 34 and 36 and levers 42 have upper ends thereof fixed to said shafts as are gears 44.

Shafts 46 and 48 are rotatable in the lower ends

of the levers 42, the latter being the driving shaft for one of the rolls 16.

As shown in Fig. 5 a cylinder 50 is fixed to wall 9 in which a piston is reciprocable and from this a rod 52 extends that carries a rack 54 in mesh with gears 44. As the rod 52 is moved up or down, the levers 42 are swung towards and away from one another to move the ends of the rolls 16 towards and away from one another.

A shaft 56 is oscillatable in bearings such as 58 secured to wall 4 and a plate 60 is fixed to said shaft. A motor 62 is fixed to the plate 60 and a pulley 64 fixed to a shaft 66 thereof is connected by a belt or belts 68 to a pulley 70 fixed to driving shaft 48.

The parts are so arranged that the weight of the motor 62 tensions the belts 68 and allows movements of the lever 42 in which shaft 48 is journaled. An adjusting screw 72 is rotatable relative to wall 4 and a dog 74 in engagement therewith and engageable with plate 60 may be adjusted to limit movement of the plate in a counterclockwise direction.

The rolls 16 are preferably formed from a stack of yieldable discs 17 which may be made from fabric or the like adapted to be charged with abrasive. Said discs are held in roll forming relation by collars 19 secured to shafts 21.

The ends of roll shafts 21 and the shafts 46 and 48 are provided with interfitting tongues and grooves, as shown, and sleeve members 23 are slidable relative to the shafts to hold them in operative engagement, see Figs. 4 and 5.

Retainers 80 are pivoted at 82 to walls 8 and are adapted to be disposed rearwardly of the members 23 to hold them in shaft coupling positions. The members 80 may be elevated to permit longitudinal movement of members 23 so that the ends of the roll shafts and shafts 46 and 48 may be disconnected and the rolls removed.

Mechanism for operating the blade supporting mechanism will now be described with particular reference to Figs. 10, 11 and 12.

Guide members 90 vertically disposed have upper and lower ends secured to an upper wall 3 of the housing and a lower plate 92 secured to the wall 12 thereof. These guides are arranged to provide a guideway for a carriage 94 which is reciprocable vertically therebetween.

A cylinder 96 has its lower end secured to member 92, a rod 98 extends upwardly from a piston reciprocable therein, and is secured to the upper part 100 of carriage 94.

Lateral extensions 102 of the carriage 94 have upper and lower rolls 104 journaled therein. A plate 106 horizontally disposed is arranged between the rolls 104 for longitudinal movements back and forth. As the rod is moved up and down by rod 98 the carriage is moved so as to move the plate 106 which may move longitudinally relative to the carriage.

A cylinder 110 is fixed to the carriage and a rod 112 of a piston therein is connected to a member 114 fixed to plate 106 whereby the plate may be reciprocated back and forth relative to the carriage which as aforesaid may be moved up and down relative to members 90.

A plate 116 is slidable in guides 118 fixed to plate 92. Rods 120 fixed to member 106 extend downwardly and are slidable through said plate 116 and bearings 122 fixed thereto. These rods 120 carry on their lower ends a longitudinal bar 124, see Fig. 1.

Hangers 126 fixed to opposite ends of member 75

124 are provided, see Fig. 8. These are adapted to receive and support work holder adapted to carry a plurality of knife blades suspended therefrom so that as the carriage moves up and down and the member 106 moves back and forth the blades are moved between and relative to the surfaces of the rolls 16.

A work holder to be supported by the hangers may take any desired form and will depend on 10 the work to be operated upon by the apparatus. In Figs. 13 and 14 a holder is shown which includes plate members 130 which are hinged together at 132 and receive upper ends of work such as blades W that depend therefrom. The 15 members 130 are held in work clamping relation by clamp screws 134 and end members 136 fixed to plates 130 are receivable in and are supported by the hangers 126 so that the blades may be disposed between the rolls 16 and moved 20 up and down as well as longitudinally relative thereto.

Means for bringing about relative movements of the rolls relative to one another and relative to the work supporting means relative 25 thereto will be described with reference to Fig. 15.

A constant delivery pump 140 is operatively connected to and driven by a motor 142 and the suction of the pump is connected by a pipe 30 144 to a tank 146. The components described may be located in the lower portion of the housing and pipes extend from the pump and tank to the cylinders 50, 56, 96 and 110 with various 35 valves in association therewith which may be located as may be convenient for their operation.

A pipe 148 extends from the discharge side of pump 140 to a two-way valve 150 which is manually operable. A pipe 152 extends from 40 valve 150 to a pipe 154 which is connected to a pipe 156 leading to the lower ends of cylinders 50. A pipe 156 extends from the other side of valve 150 to a pipe 158 connected to the upper ends of cylinders 50.

45 A pipe 160 connects tank 146 to discharge of pump 140. A pipe 162 extends from pipe 160 to valve 150 and a valve 164 is disposed in said line 160.

The valve 164 will be of the adjustable pressure relief type so constructed and arranged that fluid such as oil delivered by the pump 140 will be delivered to the tank when a certain predetermined pressure in pipe 160 is exceeded.

It will be assumed that the cylinders 50 are in 50 operation as is the motor 62 and the pump and motor 140 and 142.

With the cylinders 50 connected to the pump as described and shown and the valve 164 adjusted for a certain pressure, the piston rods 52 are held against downward movements by this pressure. That is, the separation of levers 42 and the rolls 16 carried thereby is resisted by the pressure in pipe 148 and the pressure may be any certain pressure according to the adjustment of valve 164.

The certain pressure will be such as will cause the rolls 16 to engage the work or blades with the desired pressure while the rolls are rotating thereby to obtain the desired abrasive action on blades of a certain thickness.

However, should certain blades have a greater thickness than normal, the rolls 16 and thereby levers 42 are separated so as to move rods 52 downwardly overcoming the resistance offered by the pressure. Thus, while blades of normal

thickness are between the rolls 16 a predetermined pressure is applied to the blades by the rolls but with thicker blades the rolls separate to accommodate them but apply the predetermined pressure. In other words the rolls move back and forth to accommodate relative thick and thin blades but apply a predetermined pressure which may be as desired.

It will be understood that the rolls at one end may be separated independently of the relative spacing of the other ends of the rolls so that the longitudinal axes of the rolls is not necessarily parallel at all times but is such as to apply the predetermined pressure to the rolls regardless of the relative thickness of the blades therebetween.

When it is desired to separate the rolls 16, valve 150 is operated to connect the upper ends of cylinders 50 to the discharge of pump 140.

A pipe 170 extends from a discharge of pump 140 and has a control valve 172 therein. Pipes 174 and 176 extend from 170 to two-way valves 178 and 180 and have volume control valves 182 and 184 therein. Pipes 186 and 188 extend from valves 178 and 180 to one end of cylinders 96 and 110. Other pipes 190 and 192 extend from opposite ends of cylinders 96 and 110 to the valves 178 and 180 and pipes 194 and 196 extend from valves 178 and 180 to the tank 146.

The valves 178 and 180 are of the well known form having levers 198 engageable by collars 200 which are adjustable on rods 98 and 112. As the rods are moved back and forth the collars act on the levers of the valves to operate them all to the end that the rods are operated in alternate directions accordingly as pressure is applied alternately to opposite ends of the cylinders.

The valves 182 and 184 are adjustable to control the volume of fluid delivered to the cylinders through the valves 178 and 180. The collars 200 are adjustable on rods 98 and 112 to control the length of stroke of said rods. Thus the speed of reciprocation of rods 98 and 112 is variable as are the strokes thereof and the operation of said rod is independent of one another.

Thus the member 124 may have any desired longitudinal and up and down movement thereby moving the blades between the rolls 16 for the desired abrasive action.

It will be observed that the rolls may be easily connected to and disconnected from their supporting and driving means which is so constructed and arranged that the rolls at their one ends may move towards and away from one another independently of the opposite ends while the work support may have independent longitudinal and up and down movements of variable magnitude all to the end that various abrasive operations may be performed on the work.

In operation a plurality of blades W are secured in the holder shown in Figs. 13 and 14 and opposite ends of the holder are placed in the hangers 126 so that the blades are suspended thereby for the action of rotating rolls 16 therebelow which are journalled in swingable arms 42. The arms are swung towards and away from one another and towards and away from the blades therebetween. Carriage 94 is reciprocable up and down and horizontal plate 106 from which hangers 126 are suspended is reciprocable back and forth in the carriage so that the blades between the rolls 16 are moved up and down and back and forth, between the rolls 16. The carriage is reciprocated through cylinder 96, the plate 106 is reciprocated through cylinder 110 and

the arms supporting the rolls 60 are swung back and forth through cylinders 50. Said cylinders are shown in Fig. 15. The pump 140 and tank 146 supply fluid under pressure and together with piping connections and various valves the operation of the mechanism is controlled. The rolls 16 are held against separation by valve 150 controlling flow of fluid to cylinders 50. Or the separating tendency of the roll levers is resisted by pressure in cylinders 50. Thereby the desired pressure of the rolls on the blades may be obtained. Valve 150 may of course be operated to release pressure for separation of the rolls. Valves 178 and 180 for cylinder 110 and 96 are actuated in opposite directions by rods and collars of the pistons of said cylinders so that the pistons of the cylinders are reciprocated in opposite directions whereby carriage 94 is reciprocated vertically up and down and the plate 106 is reciprocated in the carriage horizontally. In this way the blades are reciprocated vertically up and down and horizontally back and forth between the rotating rolls.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. A machine of the class described comprising in combination, spaced pairs of relatively movable roll supports, a pair of rolls, engageable connections between opposite ends of the rolls and the supports of the pairs thereof, separate means at opposite ends of said rolls for driving one of them, independent pressure operated means at opposite ends of the rolls operatively connected to said supports for moving the supports of the pairs towards and away from one another, holder supporting means, a holder for a plurality of depending work pieces disposed between said rolls, actuating means for moving said holder supporting means up and down and back and forth whereby work pieces therebetween are moved longitudinally of the rolls and in planes at right angles thereto.

2. A machine of the class described comprising in combination, spaced pairs of relatively movable roll supports, a pair of rolls, engageable connections between opposite ends of the rolls and the supports of the pairs thereof, separate means at opposite ends of said rolls for driving one of them, independent pressure operated means at opposite ends of the rolls operatively connected to said supports for moving the supports of the pairs towards and away from one another, holder supporting means, a holder for a plurality of depending work pieces disposed between said rolls, actuating means for moving said holder supporting means up and down and back and forth whereby work pieces therebetween are moved longitudinally of the rolls and in planes at right angles thereto, said roll supports including relatively swingable levers, and said independent pressure operated means including a cylinder having a piston rod operatively connected to said levers.

3. A machine of the class described comprising

in combination, spaced pairs of relatively movable roll supports, a pair of rolls, engageable connections between opposite ends of the rolls and the supports of the pairs thereof, separate means at opposite ends of said rolls for driving one of them, independent pressure operated means at opposite ends of the rolls operatively connected to said supports for moving the supports of the pairs towards and away from one another, holder supporting means, a holder for a plurality of depending work pieces disposed between said rolls, actuating means for moving said holder supporting means up and down and back and forth whereby work pieces therebetween are moved longitudinally of the rolls and in planes at right angles thereto, said actuating means including a piston operated carriage slideable up and down and a piston operated plate member reciprocable therein provided with members from which said holder is suspended.

4. In a machine of the class described, supporting means, spaced pairs of roll supports having shafts rotatable therein, a pair of coaxing rolls, engageable connections at opposite ends of said rolls and adjacent ends of said shafts, separate means at opposite ends of said shafts for rotating one of said rolls, including motors and driving connections between said motors and said rolls, and mounting means for said motors adapted to permit movement of said motors to maintain predetermined tension of said driving connections, said engageable connections including engageable members at opposite ends of said rolls and shafts and holding means slideable thereon to releasably hold said members in engagement.

5. In a machine of the class described, supporting means, spaced pairs of roll supports having shafts rotatable therein, a pair of coaxing rolls, engageable connections at opposite ends of said rolls and adjacent ends of said shafts, separate means at opposite ends of said shafts for rotating one of said rolls, including motors and driving connections between said motors

and said rolls, and mounting means for said motors adapted to permit movement of said motors to maintain predetermined tension of said driving connections, said engageable connections including engageable members at opposite ends of said rolls and shafts and holding means slideable thereon to releasably hold said members in engagement, and movable means to retain said holding means in holding positions.

6. A machine of the class described comprising in combination, spaced pairs of relatively swingable roll supporting levers, a pair of rolls, engageable connections between opposite ends of the rolls and the levers of the pairs thereof, separate means at opposite ends of the pair of rolls for driving one of them, independent pressure operated means at opposite ends of the pair of rolls and operative connections with said levers for swinging the levers of the pairs towards and away from one another, holder supporting means, a holder for a plurality of depending work pieces disposed between said rolls, actuating means for moving said holder supporting means up and down and back and forth whereby work pieces therebetween are moved longitudinally of the rolls and in planes at right angles thereto, said actuating means including a piston operated carriage slideable up and down and a piston operated plate member reciprocable therein provided with members from which said holder is suspended.
